UNITED STATES PATENT OFFICE.

FERDINAND BIRCHBAUER, OF BALTIMORE, MARYLAND, ASSIGNOR OF ONE-HALF TO
JOSEPH H. FALLIN, OF BALTIMORE, MARYLAND.

INTERNAL-COMBUSTION ENGINE.

1,423,477.

Specification of Letters Patent. Patented July 18, 1922.

Application filed September 16, 1919. Serial No. 324,121.

To all whom it may concern:

Be it known that I, FERDINAND BIRCHBAUER, a citizen of the United States, residing at Baltimore, in the State of Maryland, have 5 invented certain new and useful Improvements in Internal-Combustion Engines, of which the following is a specification.

This invention relates to improvements in internal combustion engines, and has for its 10 object to provide an engine, of the type described, of greater efficiency and power than the present internal combustion engines of similar size.

The invention consists of the novel construction and arrangement of the parts and combination of parts hereinafter more fully set forth in the following specification and pointed out in detail in the appended claim.

In the accompanying drawing—

20 Figure 1 is an elevation of my invention, the crank-case being shown in section.

Figure 2 is a vertical section of the piston cylinder showing the pistons at their extreme stroke.

25 Figure 3 is a detail plan view of the ring surrounding the lower end of the cylinder and to which the cranks of the upper piston are connected.

30 Referring to the accompanying drawing forming part of this specification and in which like reference numerals designate like parts throughout the several views thereof, 1 designates the piston cylinder which is connected to and has its lower end projecting into the crank-case 2. The said cylinder 1 is provided with two pistons 3 and 4, the upper piston 3 being connected by the rod 5 to the cross-head 6 which latter is connected to the rods 7 the said rods 7 project down through the plugs 8 and 9 and have their lower ends connected to the ring 10 which latter is adapted to slide up and down on the lower end of the cylinder 1 and is connected by the rods 11 to the cranks 40 12 on the crank-shaft 13. The said cranks 12 are set at the same degree and work in unison, both being operated by the upper piston 3 the lower piston 4 is connected by the rod 14 to the crank 15 on the crank-shaft 13. The cylinder 1 is provided with an intake valve 16 which controls the opening 17 through which the gas is supplied to the cylinder 1. On the downward stroke of the upper piston 3 the intake valve 16 is unseated, which allows the gas to pass to be

drawn through the opening 17 and passes through the port 18 to the chamber above the piston 3 and on the upward stroke of the piston 3 the gas above the said piston 3 will be forced through the port 18 and pass 60 down the passage 19 and through the ports 20 below the piston 3 and into the chamber by the pistons 3 and 4 and when the said pistons 3 and 4 move towards each other the gas will be compressed in the chamber by 65 the said pistons 3 and 4 where it will be fired by the spark from the spark plug 21 and as said pistons move apart the exhaust will pass through the ports 22, passage 23 and out through the exhaust opening 24. 70 This operation is repeated at each firing of the gas.

It will thus be seen that each time the firing takes place the cylinder will be forced apart and each operating the crank-shaft at the 75 same time thus creating practically twice the power of an engine of similar size and only one cylinder.

It is obvious that any number of cylinders desired may be employed.

Having thus described my invention what I claim is:

In an internal combustion engine, the combination of the cylinder having a passage at its upper end, an intake opening 80 in said passage, and ports connecting said passage with the combustion chamber of said cylinder, a valve to control said intake opening, a passage at the lower end of said cylinder, an exhaust opening to the passage 85 at the lower end of the cylinder, and ports leading from the combustion chamber to the passage at the lower end of the cylinder, a crank-case into which the lower end of said cylinder projects, a crank-shaft mounted in 90 said case and having two cranks set at the same degree and one crank set opposite to the first mentioned two cranks, two pistons within said cylinder, a rod connecting the lower piston with the crank shaft, a cross-head above said cylinder, a rod connecting the upper piston with the said cross-head, a ring surrounding the lower end of the said cylinder, two rods connecting the cross-head with said ring, and rods connecting the 95 said ring with the first mentioned two cranks on the crank-shaft.

In testimony whereof I affix my signature.

FERDINAND BIRCHBAUER.
